UNITED STATES PATENT OFFICE

ANTON YURKOVITCH, OF PITTSBURGH, PENNSYLVANIA

ADJUSTABLE FLUE CONNECTION

Application filed March 7, 1932. Serial No. 597,335.

This is a continuation in part of my companion application Serial No. 583,629, filed December 29, 1931, and represents a construction adapted for the purposes set forth in that application but which is simpler, less expensive and of greater versatility.

In general the objects and advantages of the present invention are based upon those set forth in my aforesaid companion application but the present invention offers even further advantages due to its construction.

Such other or additional objects and advantages will either be apparent hereinafter or will be pointed out as this description proceeds.

In the accompanying drawing, I have illustrated features of the present invention, and in such drawing:

Figure 1 is a perspective view of a simplified form of the present invention.

Fig. 2 is a front view showing the device in operative association with a fragment of brickwork in which it is ordinarily embedded.

Fig. 3 is a fragmentary detail of a modified form of bolt socket.

Fig. 4 is a side elevation of a modified form of washer having spaced peripheral recesses.

Fig. 5 is a section on line V—V of Fig. 4.

Fig. 6 is a fragment of a modified form of the invention, wherein a spacing element is used, along the lines of my aforesaid copending application; and

Fig. 7 is a sectional elevation through a still further modified form of spacer.

Corresponding numerals designate similar parts throughout the several views of the drawing:

Referring to the drawing, the construction of my invention is generally embedded in brickwork 10 or the like, a fragment of which is shown in Fig. 2 and more detailed reference to which will be found in my aforesaid companion application. As in said companion application the invention comprises a ring 11 which may be suitably cast from any desired material but preferably is

cast of metal or alloy such as copper, brass, stainless steel or other non-corrodible fire-

proof material. This ring may be made other than by casting if so desired depending upon the material used and hence its characteristics and may be of any suitable diameter and wall thickness as explained in my aforesaid application.

Whatever the precise dimensions or material, the ring 11 is provided with diametrically opposite socketed plates, each composed of a metallic rectangular plate member 12 riveted, welded or otherwise suitably secured to the exterior of the ring 11 and these plates are preferably contoured to the curvature of the ring so that a snug, firm fit is secured. Extending at right angles from these plates 12 are the metallic bosses or extensions 13, preferably integral with the plates, said bosses or extensions being tapped out and suitably interiorly threaded for a purpose to be hereinafter explained. As is apparent from Fig. 2, the plates and bosses become embedded in the brickwork 10 preventing any angular rotation or other movement of the ring when once positioned. Said ring is also provided with diametrically opposite apertures 14 which register with threaded bosses 13 on plates 12 aforesaid.

Screw-threaded bolt members 15 are provided as shown and in practice these are screwed into the bosses 13 passing through apertures 14 and these apertures 14 are purposely made at least slightly larger than the threaded bolts to provide for free and easy access of the bolts to the threaded bosses and for equally simple withdrawal when required. These bolts are of suitable length and preferably extend toward each other leaving only a relatively small free space between them.

As will be understood from the foregoing and from the aforesaid companion application, the invention is adapted to accommodate stove pipes of various sizes and at various angles and positions. For this reason, the ring 11 is made at least slightly larger in diameter than the largest diameter of stove pipes used and the bolts 15 extend toward each other far enough so that stove pipes of minimum diameter can be accommodated.

The rear edge of the stove pipe 11a is preferably recessed or slotted as at 16 so that the

100

bolts being in position, the stove pipe can be positioned with the bolts in the slots 16.

Previously, washer members 17 of suitable metal or fire-proof material are threaded on the bolts so that when the stove pipe end is positioned on said bolts the washers can be moved until they snugly rest against the exterior of the stove pipe section. These washers are suitable metal disks of appropriate size and having a central aperture 18 screw threaded interiorly at 19 for use on said bolts. As shown in Figs. 2, 4 and 5, said washers may be provided with spaced peripheral notches or recesses 20 so that if desired or necessary a tool can be inserted in any of said notches or recesses to turn said washers into tighter or looser positions.

When the stove pipe has been assembled on the bolts and the washers 17 snugly positioned against the stove pipe, suitable nuts such as wing nuts 21 are positioned on the bolts against the inside of said stove pipe section 11a and these are tightened until the whole assembly is firm and relatively rigid, intermediate washers 22 being generally employed for the usual purposes.

As shown in Fig. 3, the bosses 13' may be interiorly tapered toward their outer ends as at 23 so that bolt 15 abuts against the end of the boss and wedges itself in position preventing movement of the bolt too far and thus wasting a portion of the bolt length although such excess positioning would do no other harm.

Fig. 6 illustrates a construction which is identical with Fig. 4 of my aforesaid companion application except that the spacer 26 which may be used between the stove pipe section 18' and the ring 11', as clearly set forth in said application, is interiorly screw threaded thus making a more mobile yet firm and adaptable construction. In Fig. 6, 21' represents a screw-threaded bolt having an enlarged head 23', spacer 26 of suitable metal being so chosen as to size, that it substantially completely fills up the space between ring 11' and stove pipe sections 18'. The assembly is completed by a washer 25' and wing nut 24'. Fig. 7 illustrates a metallic spacer 27' internally screw threaded at 27" adapted to be substituted for the spacer 26' of Fig. 6 when a stove pipe of larger diameter is used in connection with the invention.

It will be clear, therefore, that I have provided a modified form of adjustable flue connection wherein a simpler and more versatile construction has been produced. The further advantages are secured that the stove pipe section need not be centered with respect to the ring 11 but in order to meet conditions in some instances it will be understood that the stove pipe section could be accommodated in a decentered position, that is, one in which it would not be concentric to the ring and this could be clearly accomplished merely by the

appropriate positioning of the washers 17 and wing nuts 21, the arrangement being made further possible by the relatively long bolt members 15 thus affording a wide variety of position and of stove pipe section.

I am not limited however precisely to the above indicated construction but may make suitable further or additional modifications, substitutions, variations or omissions without departing from the spirit and scope of the present invention and of the sub-joined claims. For example, the decentered positioning of the stove pipe section or flue could also be effected by utilizing unequally sized spacers. It is to be understood that the stove pipe or flue section shown is a part of the normal installation and that it is not furnished as a part of the present invention, it being only necessary, in order to install the present invention to recess or slot such stove pipe or flue section so that it will receive the bolts 15 or the like.

What I claim as new and desire to secure by Letters Patent is:

1. An adjustable flue connection comprising a ring member provided with diametrically opposite plates having hollow threaded bosses extending therefrom, there being apertures in said ring aligned with said bosses, screw-threaded bolts extending through said apertures and into said bosses, a stove pipe or flue section being adapted to be positioned on said bolts in such a manner as to accommodate stove pipe or flue sections of various sizes and in various positions, washers on said bolts adapted to snugly abut the exterior of said stove pipe or flue section and nuts on said bolts snugly adapted to abut the interior of said pipe or flue section.

2. An adjustable flue connection comprising a ring member provided with diametrically opposite plates having hollow threaded bosses extending therefrom, there being apertures in said ring aligned with said bosses, screw-threaded bolts extending through said apertures and into said bosses, a stove pipe section being adapted to be positioned on said bolts in such a manner as to accommodate stove pipe sections of various sizes and in various positions, washers on said bolts adapted to snugly abut the exterior of said stove pipe section and nuts on said bolts adapted to snugly abut the interior of said stove pipe section, said plates conforming to the curvature of said ring and being suitably secured thereto and said bosses extending unitarily therefrom substantially at right angles thereto.

3. An adjustable flue connection comprising a ring member provided with diametrically opposite plates having hollow threaded bosses extending therefrom, there being apertures in said ring aligned with said bosses, screw-threaded bolts extending through said apertures and into said bosses, a stove pipe

section being adapted to be positioned on said bolts in such a manner as to accommodate stove pipe sections of various sizes and in various positions, washers on said bolts adapted to snugly abut the exterior of said stove pipe section and nuts on said bolts adapted to snugly abut the interior of said stove pipe section, said plates conforming to the curvature of said ring and being suitably secured thereto and said bosses extending unitarily therefrom substantially at right angles thereto, the ends of said bosses being tapered to an effective size smaller than said bolts.

4. An adjustable flue connection comprising a ring member provided with diametrically opposite plates having hollow threaded bosses extending therefrom, there being apertures in said ring aligned with said bosses, screw-threaded bolts extending through said apertures and into said bosses, a stove pipe section being adapted to be positioned on said bolts in such a manner as to accommodate stove pipe sections of various sizes and in various positions, washers on said bolts adapted to snugly abut the exterior of said stove pipe section and nuts on said bolts adapted to snugly abut the interior of said stove pipe section, said washers being internally threaded and having spaced peripheral notches.

5. An adjustable flue connection comprising a ring member provided with diametrically opposite plates having hollow threaded bosses extending therefrom, there being apertures in said ring aligned with said bosses, screw-threaded bolts extending through said apertures and into said bosses, a stove pipe or flue section of various sizes and at various angles being adapted to be positioned on said bolts, washers on said bolts adapted to snugly abut the exterior of said stove pipe or flue section after insertion thereof and nuts on said bolts snugly adapted to abut the interior of said pipe or flue section after such insertion, said stove pipe or flue section being decenterable relative to said ring.

6. An adjustable flue connection comprising a ring, bolts diametrically passing through said ring toward the center thereof, said bolts being exteriorly threaded, a stove pipe section adapted to be predeterminedly positioned on said bolts, spacers adapted to be threaded on said bolts between said stove pipe section and said ring and substantially the width of the space therebetween, and means for maintaining said members as aforesaid.

7. An adjustable flue connection comprising a ring, bolts diametrically passing through said ring toward the center thereof, said bolts being exteriorly threaded, a stove pipe section adapted to be predeterminedly positioned on said bolts, spacers

adapted to be threaded on said bolts between said stove pipe section and said ring and substantially the width of the space therebetween, and means for maintaining said members as aforesaid, said spacers being of unequal size.

8. An adjustable flue connection comprising a ring, bolts diametrically passing through said ring toward the center thereof, said bolts being exteriorly threaded, a stove pipe section adapted to be predeterminedly positioned on said bolts, spacers adapted to be threaded on said bolts between said stove pipe section and said ring and substantially the width of the space therebetween, and means for maintaining said members as aforesaid, said bolts having enlarged heads abutting the exterior of said ring, and said stove pipe section being suitably slotted for positioning as aforesaid.

9. In an adjustable flue connection of the character described, a ring member for non-rotatable disposition in a chimney, having diametrically opposite apertures, arcuate plates on the outer surface of said ring overlying said apertures, and apertured bosses extending from said arcuate plates to prevent rotation of said ring-member, the apertures in said bosses registering with those in said ring.

10. In an adjustable flue connection of the character described, a ring member adapted to be embedded in a chimney, having diametrically opposite apertures, arcuate plates on the outer surface of said ring overlying said apertures, and apertured bosses extending from said arcuate plates to prevent rotation of said ring member, the apertures in said bosses registering with those in said ring, said bosses being internally threaded and being perpendicular to a tangent of said ring at said apertures.

11. In an adjustable flue connection of the character described, a ring member, adapted to be embedded in a chimney, having diametrically opposite apertures, arcuate plates on the outer surface of said ring overlying said apertures, and apertured bosses extending from said arcuate plates to prevent rotation of said ring member, the apertures in said bosses registering with those in said ring, the outer ends of said apertures being provided with an appreciably convergent portion.

12. In an adjustable flue connection of the character described, a ring member adapted to be embedded in a chimney, having diametrically opposite apertures, arcuate plates on the outer surface of said ring overlying said apertures, and apertured bosses extending from said arcuate plates, the apertures in said bosses registering with those in said ring, and threaded bolts in said bosses extending radially inwardly, the bosses aforesaid serving to prevent rotation of said ring member and to receive one end of said bolts.

13. In an adjustable flue connection of the character described, a ring member adapted to be embedded in a chimney, having diametrically opposite apertures, arcuate plates on the outer surface of said ring overlying said apertures, and apertured bosses extending from said arcuate plates, the apertures in said bosses registering with those in said ring, and threaded bolts in said bosses extending radially inwardly, nut and washer instrumentalities on said bolts, said bosses serving to prevent rotation of said ring member and to receive one end of said bolts.

14. An adjustable flue connection of the
